GRINDING MACHINE STEADY REST

Carl G. Flygare, Worcester, Mass., assignor to
Norton Company, Worcester, Mass., a corpora-
tion of Massachusetts

Application July 21, 1936, Serial No. 91,729

8 Claims. (Cl. 51—238)

This invention relates to a grinding machine, and more particularly to a work steadyng rest for a cylindrical grinding machine.

One object of this invention is to provide a simple and thoroughly practical work steadyng rest for a grinding machine. Another object of the invention is to provide a steady rest which is simple in operation and adjustment for supporting a cylindrical work piece during a grinding operation. A further object of the invention is to provide a steady rest in which opposed bearing shoes are provided to steady the work and thereby prevent vibration during a grinding operation. Another object of the invention is to provide a steady rest in which one work steadyng shoe is maintained in an adjustably fixed position and a second shoe is moved into rigid engagement with the work during a grinding operation. A further object of the invention is to provide a steady rest for a grinding machine in which the work steadyng shoes are readily adjustable transversely. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is an end elevation of the improved steady rest, showing the work steadyng shoes in an operative position in engagement with the work and the grinding wheel in an operative position;

Fig. 2 is a plan view of the steady rest as shown in Fig. 1;

Fig. 3 is an end elevation, on a reduced scale, showing the upper steady rest shoe removed to an inoperative or loading position; and

Fig. 4 is a fragmentary sectional view, on an enlarged scale, taken approximately on the line 4—4 of Fig. 1.

As illustrated in the drawing, the improved steady rest has been illustrated as applied to an ordinary cylindrical grinding machine comprising a longitudinally movable table 10 which serves to rotatably support a work piece 11 on the usual head and footstock (not shown). A rotatable grinding wheel 12 is provided to grind the work piece to the required size.

In order to support the work piece 11 during the grinding operation so as to prevent vibration

thereof, an improved steady rest is provided comprising a steady rest base 15 having surfaces 16, 17 and 18 which mate with correspondingly shaped surfaces on the upper surface of the table 10 and is arranged to be clamped in position on the table 10 by means of a clamping block 19 and a screw 20. The base 15 serves as a support for a transversely movable steady rest frame 21. The steady rest frame 21 is provided with a dovetailed slideway 22 which mates with a correspondingly shaped dovetailed way 23 formed integral with the steady rest base 15. A flat slideway 24 is provided on the under surface of the steady rest frame 21 which mates with a corresponding slideway on the base 15 and serves to support the rear end of the frame 21.

In order to adjust the steady rest in setting up the rest for a given grinding operation, a manually operable adjustment is provided to adjust the steady rest frame 21 transversely relative to the steady rest base 15. This mechanism may comprise a rotatable screw 27 which is rotatably supported in a bearing 28 in the upwardly extending projection 29 of the steady rest base 15. The screw 27 is screw threaded into a correspondingly threaded aperture 30 in the steady rest frame 21. The outer end of the screw 27 is provided with a knurled adjusting knob 31. In order to facilitate adjustment of the frame 21, a graduated dial 32 is carried by the screw 27 adjacent to the knob 31. A zero or index point 33 is mounted on the upwardly projecting portion 29 of the steady rest base 15. By rotation of the knob 31 in either direction, the steady rest frame 21 may be adjusted to the required extent.

A steady rest shoe is provided on said frame for supporting the surface of the work piece 11 preferably below its axis of rotation. In the construction as illustrated, the lower steady rest shoe comprises two spaced shoes 40 and 41 which are provided for engagement with the under surface of the work piece 11 below the work axis. The shoes 40 and 41 are arranged so that they may be adjusted toward and from the axis of the work piece 11 to facilitate setting up the steady rest. In the preferred construction, as illustrated in the drawing, the steady rest shoes 40 and 41 are supported at one end of a pivotally mounted arm 42 which is connected by a stud 43 with a boss 44 projecting from the upper surface of the steady rest frame 21. An adjusting screw 45 is provided to adjust the outer end of the arm 42 vertically to position the shoes 40 and 41 in the desired relationship with the axis of the work

piece 11. The arm 42 is arranged so that it may be clamped and held in adjusted position during the grinding operation. The lever 42 is provided with an elongated slot 46. A clamping screw 47 supported by an upwardly projecting portion 48 of the steady rest frame 21 rides in the elongated slot 46 and serves to clamp the lever or arm 42 in adjusted position. A spring 48 interposed between the steady rest frame 21 and the outer end of the lever 42 serves to dampen any vibration of the lever during grinding.

10 The lower steady rest shoe including the work engaging shoes 40 and 41 are adjusted vertically so that their bearing surfaces will support a work piece of a finished size. When a work piece to be ground is inserted in the machine and the head and footstock centers are brought into a supporting position, the axis of the work piece will be sprung by the steady rest during the initial grinding operation. As the grinding operation proceeds, the axis of the work approaches its normal position, which is reached when the work piece is reduced to the predetermined size.

15 It is desirable to provide an adjustable steady rest shoe to hold the work piece 11 in engagement with the shoes 40 and 41 during the grinding operation so as to prevent vibration thereof. A steady rest shoe 55 is arranged to engage the upper surface of the work piece 11 above the axis 20 of rotation thereof and at a point substantially diametrically opposite to the steady rest shoes 40 and 41. The steady rest shoe 55 is preferably arranged so that it may be moved to and from an operating position to facilitate loading of work pieces into the machine. In the preferred construction, the shoe 55 is mounted on a pivotally mounted arm 56 which is connected at its lower end to the steady rest frame 21 by means of a stud 57. The shoe 55 is mounted so that it may 25 be adjusted toward and from the work axis in setting up the machine for various sizes of work. In order to obtain the desired adjustment of the shoe 55, the stud 57 is preferably provided with an eccentric portion 58 whereby rotation of the 30 eccentric will adjust the arm 56 relative to the frame 21 so that the shoe 55 engages the work as required. A nut 59 on a threaded portion 60 of the stud 57 serves to lock the stud in adjusted position.

35 50 It is desirable to provide an actuating mechanism for the movable steady rest shoe 55 so that it may be moved rapidly to and from an operating position to facilitate loading and unloading of work pieces. A manually operable lever 65 is provided for moving the shoe 55 toward and from an operating position. The lever 65 is connected to a stud 66 supported in bosses 67 and 68 projecting upwardly from the steady rest frame 21. Toggle levers are connected between the stud 66 40 and the end of the lever 65 so that when the manually operable lever 65 is moved either upwardly or downwardly, the shoe 55 will be moved into or out of an operative position relative to the work piece 11. One end of a toggle lever 69 45 is mounted on the stud 66 and is connected so that it moves with the lever 65. The other end of the lever 69 is provided with two outwardly extending arms 70 and 71 which straddle the end of a toggle lever 72 and are connected thereto 50 by means of a stud 73. The other end of the lever 72 is connected by a stud 73 with the upper end of the shoe carrying arm 56, so that when the lever 65 is moved upwardly into the position 55 illustrated in Fig. 1, with the levers 69 and 76 72 engaging a stop 74, the shoe 55 is moved into

operative contact with the surface of the work piece 11. Similarly, when the lever 65 is moved downwardly into the position illustrated in Fig. 3, the shoe 55 is moved to an inoperative position away from the work piece 11 to facilitate removal 5 of a ground piece of work and insertion of a piece of work to be ground thereinstead.

60 It is desirable that the steady rest shoe 55 be maintained rigidly in engagement with the work at a desired operating pressure during the grinding operation. This is preferably accomplished by providing a yieldable connection between the toggle levers 69 and 72. The toggle lever 72 is provided with a cut-out portion 75 within which a plunger 76 may slide. The reduced portion 77 15 of the plunger slides within a hole 78 within the lever 71. The head of the plunger 76 engages a slabbed-off surface 79 on the stud 73 and serves to prevent the stud 73 from turning as the toggle levers 69 and 72 are actuated. A spring 80 surrounds the stud 77 and is interposed between the head 76 of the plunger and a surface 81 at the end of the cut-out portion 75.

When the toggle levers 69 and 72 are moved into an operative position (Fig. 1), the lever 65 is 25 moved in a clockwise direction to position the shoe 55 in rigid engagement with the work piece 11. During this movement, the spring 80 is compressed. As the size of the work piece 11 is reduced during grinding, the compressed spring 80 30 maintains the shoe 55 rigidly in engagement with the periphery of the work piece 11.

A spring 85 is connected at one end to a stud 86 35 carried by the lever 65 and is connected at the other end to a stud 87 carried by the steady rest frame 21 and serves to hold the operating lever 65 either in an operating or an inoperative position, as desired.

The operation of this steady rest will be readily apparent from the foregoing disclosure. Assuming the steady rest shoes 40 and 41 to have been 40 adjusted in a vertical direction by means of the adjusting screw 45 and clamped in adjusted position by means of the clamping stud 47, and also assuming the steady rest frame 21 to have been 45 adjusted transversely by means of the adjusting knob 31 so that the shoes 40 and 41 are positioned to support a work piece of finished size, a work piece 11 is then inserted in the machine and the head and footstock centers are moved 50 into driving engagement with the work so as to support the work piece in operative relation therein. The operating lever 65 may then be moved from the inoperative position as illustrated in Fig. 3 into the operative position as illustrated 55 in Fig. 1, which serves to shift the toggle levers 69 and 72 into the position illustrated in Fig. 1, thereby moving the upper steady rest shoe 55 into operative engagement with the work piece 11. The 60 grinding operation may then proceed to the desired extent, after which the manually operable lever 65 may be moved downwardly into the position illustrated in Fig. 3 to again move the steady rest shoe 55 to an inoperative position so 65 as to facilitate loading of the work piece.

It will thus be seen that there has been provided by this invention apparatus in which the various objects hereinabove set forth together with many thoroughly practical advantages are 70 successfully achieved. As many possible embodiments may be made of the above invention and as many changes might be made in the embodiment above set forth, it is to be understood that all matter hereinbefore set forth or shown in the ac- 75

companying drawing is to be interpreted as illustrative and not in a limiting sense.

I claim:—

1. In a steady rest for a grinding machine, a steady rest frame, an adjustable work steadyng shoe arranged to engage the work below the work axis, means to adjust said shoe relatively toward and from the work axis, a second work steadyng shoe arranged to engage the work above the work axis, and a manually operable toggle lever to move said second shoe into and away from operative engagement with the work, said toggle lever being arranged to hold said second shoe in an operative position.
2. In a steady rest for a grinding machine, a steady rest frame, an adjustable work steadyng shoe arranged to engage the work below the work axis, means to adjust said shoe relatively toward and from the work axis, means to lock said shoe in adjusted position, a second work steadyng shoe arranged to engage the work above the work axis, means to adjust the shoe relatively toward and from the work axis, and a manually operable toggle lever mechanism to move said second shoe into and away from operative engagement with the work, said toggle lever being arranged to hold said second shoe in an operative position.
3. In a steady rest for a grinding machine, a base, a transversely movable steady rest frame supported on said base, slideways on said frame mating with slideways on the base, means to adjust the frame transversely relative to the base, a steady rest shoe arranged to engage and steady a work piece, means to adjust said shoe toward or from the work axis, means to lock said shoe in adjusted position, a second steady rest shoe arranged to engage and steady the work at a point opposite to the first shoe, and means including a manually operable toggle lever connection between the second shoe and the frame to move the same to and from an operative position, said toggle lever being arranged to lock said second shoe in an operative position.
4. In a steady rest for a grinding machine, a transversely movable steady rest frame, means to adjust said frame transversely, a steady rest shoe which is arranged to engage and steady the work at a point below the work axis, means to adjust the position of said shoe relatively toward or from the work axis, means to lock said shoe in adjusted position, a second shoe arranged to engage the work piece at a point opposite the first shoe, a pivotally mounted lever on said frame to support said second shoe, and means including a manually operable lever mechanism arranged to move said shoe into or away from an operating position.
5. In a steady rest for a grinding machine, a steady rest frame, a steady rest shoe which is arranged to engage and steady the work, means to adjust the position of said shoe, a second shoe arranged to engage the work at a point opposite the first shoe, a pivotally mounted lever on said frame to support said second shoe, means including a manually operable lever mechanism arranged to move said second shoe into or away from an operating position, and a manually operable toggle lever to move said second shoe into and away from operative engagement with the work, said toggle lever being arranged to hold said second shoe in an operative position.
6. In a steady rest for a grinding machine, a base, a work steadyng shoe arranged to engage and steady the work, means to adjust said shoe relatively toward and from the work axis, a second work steadyng shoe arranged to engage and steady the work opposite to the first shoe, means to adjust the second shoe relatively toward and from the work axis, a manually operable toggle lever to move said second shoe into and away from operative engagement with the work, and yieldable connections between said toggle lever rigidly to maintain the second shoe in operative engagement with the work during the grinding operation.
7. In a steady rest for a grinding machine, a base, a transversely movable frame thereon, manual means to adjust the frame relative to the base, a lower adjustable work steadyng shoe arranged to engage and steady the work below the work axis, means to adjust said shoe relatively toward and from the work axis, a second work steadyng shoe arranged to engage and steady the work above the work axis and opposite to the lower shoe, means to adjust the second shoe relatively toward and from the work axis, a manually operable toggle lever to move said second shoe into and away from operative engagement with the work, and yieldable connections between said toggle lever rigidly to maintain the second shoe in operative engagement with the work during the grinding operation.
8. In a steady rest for a grinding machine, a base, a transversely movable slide thereon, manual means to adjust the frame relative to the base, a lower work steadyng shoe arranged to engage the work below the work axis, means including a pivotally mounted lever to support said shoe, means to adjust the position of said lever so that the shoe supports the work during the grinding operation, a second work steadyng shoe arranged to engage the work above the work axis, a pivotally mounted lever to support said shoe which is arranged to swing the shoe toward and from an operative position, an adjustable eccentric pivot stud for supporting said lever to facilitate adjustment of said shoe relatively toward and from the work axis, means including toggle levers to move said shoe into or away from operative engagement with the work piece before and after a grinding operation.

CARL G. FLYGARE.
